US00D909319S

(12) **United States Design Patent** (10) **Patent No.:** **US D909,319 S**
(45) **Date of Patent:** **** Feb. 2, 2021**

(54) **CIRCUIT BOARD**

(71) Applicant: **Impact IP, LLC**, Rocklin, CA (US)

(72) Inventor: **Taylor Nordeen**, Rocklin, CA (US)

(73) Assignee: **Impact IP, LLC**, Rocklin, CA (US)

(**) Term: **15 Years**

(21) Appl. No.: **29/740,940**

(22) Filed: **Jul. 8, 2020**

(51) LOC (13) Cl. **13-03**

(52) U.S. Cl.

USPC **D13/182**

(57) **CLAIM**

The ornamental design for a circuit board, as shown and described.

DESCRIPTION

FIG. 1 is a top and front isometric view of a circuit board, showing my new design.

FIG. 2 is a top and rear isometric view thereof.

FIG. 3 is a bottom and rear isometric view thereof.

FIG. 4 is a bottom and front isometric view thereof.

FIG. 5 is a top view thereof.

FIG. 6 is a bottom view thereof.

FIG. 7 is a rear view thereof.

FIG. 8 is a front view thereof.

FIG. 9 is a right view thereof; and,

FIG. 10 is a left view thereof.

The broken lines form no part of the claimed design.

1 Claim, 4 Drawing Sheets
